UNITED STATES PATENT OFFICE

KENNETH J. TOBIN, OF CHICAGO, ILLINOIS, ASSIGNOR TO CAMEL COMPANY, OF CHICAGO, ILLINOIS, A CORPORATION OF ILLINOIS

DOOR CHECK OR STOP

Application filed November 21, 1929. Serial No. 408,719.

This invention relates broadly to door checks or stops and more particularly to such checks or stops employed in connection with sliding doors for railway house cars.

It is the usual practice, in sliding car door construction, to utilize some means to limit the travel of doors in their opening and closing movements. Such means are known in the art as stops and generally take the form of castings. The stops for the door, effective when the door has reached, substantially, its full open position, have heretofore been secured directly to the car. As a result of this fact these stops, which are presented toward the rear edge of the door, are substantially rigid. The impact of the door at its rear edge on said stops in the opening movement of the door is great and because of the rigidity above mentioned, serious damage has often resulted in both the stops and the door.

This invention has, for an object, to obviate the damage noted above. It is also an object to provide stops for the rear edge of sliding doors which may be made substantially of wood or metal.

It is a further object to provide stops for sliding car doors, which stops are so constructed that they are flexible. It is an additional object to provide stops for car doors, which stops are secured to the car and are adapted to have yielding engagement with the doors.

Further objects and advantages of the invention will appear as the description thereof proceeds, taken in connection with the accompanying drawing, in which:

Figure 1 is a partial elevation of a house car with a slidably mounted door thereon and showing the door in dash and dot lines in full open position, coacting with the improved stop.

Figure 2 is a section taken on a plane, indicated by line 2—2 of Figure 1.

Figure 3 is a section taken on a plane, indicated by line 3—3 of Figure 1.

Figure 4 illustrates, in elevation, a modified stop construction.

Figures 5 and 6 show, respectively, sectional views taken substantially on the planes

indicated by lines 5—5 and 6—6 of Figure 4.

Referring, first, to the construction illustrated in Figures 1, 2 and 3, the numeral 10 designates a car door comprising corrugated sheets forming the panel thereof, although it is to be understood that a door of any particular construction may be employed. The door as shown is a bottom supported door and is adapted to slide upon a track 12 through means of roller hangers 11 positioned adjacent the bottom corners of the door. It is to be understood that a plurality of such hangers are employed, but that only one is disclosed, these hangers being identical in construction. For the purpose of properly guiding the door at its upper edge, a depending flange 14 secured to the side plate 22, is utilized. Coacting with this flange is a bracket member 13, which prevents inward movement of the upper edge of the door. Inward movement of the lower edge of the door is prevented by the hangers 11.

Mounted on the side of the car on which the door is hung and adapted to contact with the rear edge of said door is the full open position thereof as shown in dot and dash lines in Figure 1, is a stop mechanism forming the subject matter of this invention. This mechanism is shown as embodying, preferably, an elongated member 15, which in the present embodiment is shown as constituting a substantially T-shaped section. It is apparent, of course, that the invention is not limited to such a section and that any desired section may be employed in lieu thereof. This member is mounted on the car side by means of brackets 16 and 23, these brackets being positioned adjacent the upper and lower ends of the member 15. The brackets comprise body portions 19 and 26 respectively. The brackets also comprise attaching portions 18 and 24 respectively, through which rivets 17 and 25 are adapted to extend in order to secure said brackets to the car side. As shown, the brackets are preferably, although not necessarily, secured to the side plate and side sill of the car.

In order to reinforce and strengthen the brackets, ribs 21 and 27 connecting the body portions and attaching portions thereof, are employed.

5 The body portions of said brackets are provided with recesses 20 and 28 which are substantially T-shaped in section in order to conform to the section of the elongated member 15. Extending across the lower bracket member is a wall 30, provided with an opening 29. The purpose of this opening is to 10 permit proper disposal of any foreign matter which may find its way into the socket portion formed by the recess and the wall member. It is to be noted that, with the exception of said wall member, the two bracket members are substantially identical in construction.

15 The member 15, in its operative position, is adapted to have one of its ends seated within the socket portion of the bottom bracket and supported therein. The upper end of said bar is adapted to extend into and slightly 20 beyond the recessed portion of the upper bracket member, as clearly shown in Figure 1 of the drawing. The purpose of this construction is to permit ready removal of said member 15 for repairs thereon or for replacement thereof. The member 15 is shown as bowed or arcuated at 32 for a portion of its 25 length intermediate the brackets. The extent of this bowed or arcuated portion is merely a matter of choice, depending on proper functioning of the member. Adjacent the upper edge of the member 15 is a 30 bolt 33, extending through one of the flanges thereof. This bolt is shown as disposed a substantial distance below the lower edge of the upper bracket, this distance being somewhat smaller than the length of the member 15 disposed within the socket portion of the lower bracket member. The purpose of this 35 bolt is to prevent accidental vertical displacement of the member 15 to such an extent that the lower end thereof would be removed entirely from the socket portion of the lower bracket member.

40 It is apparent from Figure 1 that the bowed portion 32 of the member 15 is presented toward the door in the direction of the opening movement thereof. It is apparent, therefore, that as the door reaches the open position it will contact with said bowed portion which, because of the flexibility thereof, will 45 provide a cushioning effect for the door and at the same time be effective to stop the opening movement thereof. In this way the danger of damage, either to the stop or to the rear edge of the door, is avoided.

45 Referring to the modification shown in Figures 4, 5 and 6, the numeral 50 designates an elongated member which, in this modification, is shown constructed of wood. A portion of the member 15 is bowed as designated at 51. For supporting said member on the car side a pair of brackets is employed, which brackets may be secured at any desired spaced points on the car side. As shown in Figures 5 and 6, however, these brackets are secured,

preferably, to the side plate and side sill of the car. The lower bracket 52 is formed with a body portion 53 and with a flange 56 through which rivets 59 are adapted to extend to attach said bracket to the side sill 58. A bottom wall 54 is shown which, in connection with the body portion 53 of the lower bracket, provides a socket adapted to receive and support the lower end of the member 50.

55 In order to support the upper end of said member a bracket 60 is provided. This bracket comprises a body portion 61, a wall portion 62 and attaching portion 63, all of which are substantially similar to the corresponding portions of the lower bracket member heretofore described. The body portion, together with the wall portion 62, constitute a socket or recess portion into which the upper end of the member 50 is extended. The bracket is shown as secured to the depending flange of the side plate 68 by means of shouldered rivets 69. These rivets extend through elongated slots 64 formed in the attaching flange 63. The slots have positioned in them the shoulders of the rivets 69, for a purpose hereinafter referred to. The upper part of the attaching flange 63 has, extending horizontally therefrom, and preferably integral therewith, a flange 66 which is adapted to overlie and be supported upon the horizontal web 67 of the side plate. Projecting from the upper bracket is an extension 65 which, together with a portion of said bracket, forms an angular recess. Seated in this recess is a locking member which, in the present form, is disclosed as a bolt 70 having a nut 71 thereon. It will be noted that the nut 71 is adapted to be positioned in the angular recessed portion of the bracket so that unauthorized removal of said nut, when the bracket is properly positioned, is prevented. The purpose of the bolt and nut structure above referred to is to prevent accidental vertical movement of the upper bracket with a consequent release of the upper end of the member 50 from the socket portion of said bracket.

100 As heretofore noted, the connection of the upper bracket to the side of the car is made by means of rivets extending through elongated slots in the attaching portion of said bracket. The purpose of such connection is to permit, when desired, vertical movement of the bracket for removal and replacement of the member 50. By using a shouldered rivet, attachment of the bracket is effected and at the same time binding of the attaching portion is avoided. It is noted that, with the exception of the drainage opening 55 provided in the wall 54 of the lower bracket, 105 the upper and lower brackets are of substantially similar construction.

110 It is believed, in view of the foregoing, that the operation of the door stop shown in Figures 4, 5 and 6 will be apparent.

In order to remove and replace the member 15 shown in Figure 1 of the drawing, it is only necessary to remove the bolt 33 and to draw said member vertically upward out 5 of the lower bracket member and through the slot provided in the upper bracket member. It is to be understood that sufficient clearance between the member 15 and the recess in the upper bracket member is provided so that said member 15 may readily 10 be withdrawn. It is also to be understood that, in the constructions shown in Figures 1 and 4 of the drawing, the bowing or arcuating of the members 15 and 50, respectively, 15 are shown exaggerated for the sake of clarity.

In order to remove and replace the member 50 shown in Figure 4 of the drawing, the bolt 70 may be rotated from the inside of the car so that the nut 71 will ride off said 20 bolt. When this has been done the bracket 60 may be raised vertically on rivets 69 and the member 50 may readily be removed. After replacement of a new member the upper bracket may again be lowered so as 25 to receive the upper end of said member within the socket portion of said bracket and the bolt and nut 70 and 71 may again be properly positioned.

It is apparent that numerous changes may 30 be made in constructions illustrating the preferred embodiments of the invention without departing from the spirit thereof. It is to be understood that all such changes are contemplated in this invention, the scope of 35 which is limited only by the claims appended hereto.

I claim:

1. A door stop comprising an elongated 40 flexible member, brackets securing said member to a supporting structure, one of said brackets comprising a recessed portion adapted to receive one end of said member, said latter bracket being adjustable vertically relative to said member whereby the end of said 45 member may be released from the recessed portion to permit replacement thereof.

2. A door stop comprising an elongated 50 flexible member, means securing said member to a supporting structure, said means comprising a recessed portion adapted to receive one end of said member, said means being adjustable vertically relative to said member whereby the end of said member may be released from the recessed portion, said 55 securing means being provided with a projection and means on said structure coacting with said projection whereby vertical movement of said securing means is limited.

3. A door stop adapted for use on a rail- 60 way house car provided with a horizontal flange comprising, a yieldable member, bracket means for securing said member to the car, rivets extending through said bracket means and the car, said bracket means being pro- 65 vided with a flange resting on said horizontal

flange whereby partial support of said bracket means is provided.

4. A door stop for sliding doors of railway 70 house cars, said stop comprising a pair of spaced vertically aligned brackets adapted to be secured to a railway house car and a yielding member extending between and supported by said brackets, said member lying in the path of opening movement of 75 said door.

5. A door stop for sliding doors of railway 80 house cars, said stop comprising a pair of vertically spaced brackets adapted to be secured to a railway house car, said brackets being provided with aligned pockets, and a vertical yielding member positioned in the path of opening movement of said door having its ends extending into the pockets of 85 said brackets for support thereby.

6. A door stop for sliding doors of rail- 90 way house cars, said stop comprising a pair of vertically spaced brackets adapted to be secured to a railway house car, said brackets being provided with aligned pockets, and a vertical yielding member having its ends ex- 95 tends into the pockets of said brackets for support thereby, said member and said brackets lying in the path of opening movement of said door, an intermediate portion of said member extending forwardly of said brackets.

7. A door stop for sliding doors of rail- 100 way house cars, said stop comprising a pair of vertically spaced brackets adapted to be secured to a railway house car, said brackets being provided with aligned pockets, and a vertical yielding member positioned in the path of opening movement of said door having its ends extending into the pockets of said 105 brackets for support thereby, the pocket in said lower bracket being provided with a drainage opening for the disposal of foreign substances accumulating therein.

8. A door stop for sliding doors for railway 110 house cars, said stop comprising a pair of spaced vertically aligned brackets adapted to be secured to a railway house car and a member extending between and supported by said brackets, said member being bowed in the direction of said door intermediate said 115 brackets and provided with substantially straight bracket engaging portions.

9. A door stop comprising a pair of brackets, means securing said brackets in spaced 120 vertical relationship to a supporting structure, said brackets being provided with pockets and a flexible member extending into the pockets of said brackets for support thereby, said member being capable of substantially 125 vertical movement relative to said brackets and means for limiting such movement.

Signed at Chicago, Illinois, this 15 day of November, 1929.

KENNETH J. TOBIN.
